US00D881409S

(12) **United States Design Patent** (10) Patent No.: **US D881,409 S**
(45) Date of Patent: **** Apr. 14, 2020**

(54) **BIOCHIP CARTRIDGE**

(71) Applicant: **GenMark Diagnostics, Inc.**, Carlsbad, CA (US)

(72) Inventors: **Jon Faiz Kayyem**, Carlsbad, CA (US); **Tyler David Jensen**, San Diego, CA (US); **Bradford Frederick Tieman**, Encinitas, CA (US); **Darren S Gray**, San Diego, CA (US); **Sean Ford**, Oceanside, CA (US); **Dominic Aiello**, Denver, CO (US); **Peter Kroehl**, Carlsbad, CA (US)

(73) Assignee: **GenMark Diagnostics, Inc.**, Carlsbad, CA (US)

(**) Term: **15 Years**

(21) Appl. No.: **29/623,931**

(22) Filed: **Oct. 27, 2017**

Related U.S. Application Data

(63) Continuation-in-part of application No. 15/298,729, filed on Oct. 20, 2016, which is a continuation of application No. 14/538,565, filed on Nov. 11, 2014, now Pat. No. 9,498,778, and a continuation-in-part of application No. 14/062,865, filed on Oct. 24, 2013, now Pat. No. 9,957,553.

CLAIM

The ornamental design for a biochip cartridge, as shown and described.

DESCRIPTION

FIG. 1 shows a top perspective view of the biochip cartridge; FIG. 2 shows an elevation view of one end thereof; FIG. 3 shows an elevation view of an opposite end thereof; FIG. 4 shows a left-hand side elevation view of a thereof; FIG. 5 shows a right-hand side elevation view thereof; FIG. 6 shows a top plan view thereof; and, FIG. 7 shows a bottom plan view thereof. The broken lines in the drawings depict portions of the biochip cartridge that form no part of the claimed design.

1 Claim, 5 Drawing Sheets
